UNITED STATES PATENT OFFICE

GILBERT LAWRENCE SUMMERS, OF NOTTINGHAM, ENGLAND, ASSIGNOR TO WILLCOX & GIBBS SEWING MACHINE CO., OF NEW YORK, N. Y., A CORPORATION OF NEW YORK

SEWING-MACHINE PRESSER FOOT

Application filed October 6, 1923, Serial No. 666,960. Renewed March 12, 1929.

The present invention relates to presser-
feet for sewing machines and more particu-
larly to presser-feet of the type having two
work contacting bottom springs extending
5 longitudinally of and positioned at opposite
sides respectively along the bottom of the
foot and thus adapting the same for operating
either with equal thickness of fabric under
both sides of the foot or with greater thick-
ness under one side, either side, than the
10 other. This type of presser foot including
such springs has heretofore been practically
and commercially used on what is known as
the Willcox & Gibbs Sewing Machine Com-
pany's "flatlock machine", shown for ex-
15 ample in patents to Stockton Borton
1,041,574, and to A. A. Merritt 1,041,652, both
dated October 15th, 1912, and producing the
seam of Borton Patent 883, 614, dated March
20 31st, 1908.

The principal object of the present invention
is to further improve the aforesaid type
of presser foot with respect to its functioning
in flattening the seam produced in using such
25 a foot. This and other objects are attained
by the present invention which can best be
explained by reference to the accompanying
drawing illustrating what is at present be-
lieved to be the preferred structural embodi-
30 ment and expression thereof. In said draw-
ings—

Fig. 1 is a perspective view of the presser-
foot, with the trimmings deflector partly
broken away;

35 Fig. 2 is a front view in which part of the
presser-foot and part of the arm which car-
ries the movable trimmer blade are shown in
elevation, and in which the work-plate, feed-
member, and part of the work-arm support-
40 ing the work-plate, are shown in transverse
section. Two thicknesses of fabric under
one side of the presser-foot are to be joined
to a single thickness of fabric under the other
side thereof;

45 Fig. 3 is a perspective view of the rear end
of the presser-foot;

Fig. 4 is a detail view of the trimmings de-
flector;

50 Fig. 5 is a bottom view of the work contact-
ing parts of the presser foot;

Fig. 6 is a perspective view of the bottom
portion of the foot turned upside down and
with the bottom spring members removed;

Fig. 7 is a detail perspective view of the
two bottom springs;

55 Figs. 8 and 9 are diagrammatic views in
which the presser-foot is shown in transverse
section on a line approximating line $a-a$ of
Fig. 5, Fig. 8 showing said presser-foot in
engagement with two abutted edges of fabric
60 of equal thickness, and Fig. 9 showing the
presser-foot in engagement with two thick-
nesses of fabric under one side thereof abutted
to a single thickness of fabric under the
other side of the foot; and

65 Fig. 10 is a diagrammatic view illustrating
a modification and in which the presser-foot is
shown in transverse section on a line approx-
imating line $a-a$ of Fig. 5.

70 In many particulars the presser-foot here-
in illustrated is substantially that of Figs.
46 and 47 of the aforesaid Merritt Patent No.
1,041,652. 30 is the main body of the foot
having a split hub 31 adapted to be securely
75 clamped to the lower end of a presser-foot
bar movable in the head of the machine, a por-
tion of the wall of which is shown at 80 in
Fig. 1. The usual spring 81, the tension of
which may be adjusted by a nut 82, yield-
80 ingly presses the foot against the work while
permitting vertical vibration thereof in re-
sponse to upward movements of the feed. A
cross-thread carrier 32, a cross-thread hook
33, driving connections therefor, and the
85 mounting of these parts on the foot-body 30,
are substantially the same as in the said Figs.
46 and 47 of said Merritt patent. Thus, said
hook 33 is removably secured by a set-screw
to the lower end of an upright shaft 34, Fig.
90 1, rotatable in an extension 35 of the foot-
body 30. A rock-lever 36 (Fig. 1) secured to
the upper end of shaft 34 has a long arm and
a short arm, the latter connected by link 37 to
a driving part not shown in the drawing.
The long arm extends in a curve to a pivotal
connection with one end of a link 38, the other
end of said link being in turn pivotally con-
nected to a crank-arm 39 at the upper end of
a shaft 40 journaled in an upright opening in
the foot body. Cross-thread carrier 32 is de-

55

60

65

70

75

80

85

90

100

tachably secured to the lower end of shaft 40. The cross-thread hook 33 and carrier 32 operate in the manner set forth in the patents aforesaid.

5 The horizontally disposed flattened portion of the foot-body 30, which extends forward of what constitutes the shank of the foot, is notched or slotted, forming two toes or branches 41, 42 (Fig. 1) between which the 10 upturned edges of the fabric advance and are trimmed by the trimmer-blades. Fixed trimmer-blade 43 is secured to the under side of toe 42 by a clamp-block 44 and screw 45 (Figs. 1 and 2). Movable trimmer-blade 46 15 works in a horizontal opening through toe 41 and is clamped to the lower end of the trimmer-arm 47, Fig. 1, which is the same in construction and operation as arm 643 of Fig. 47 of the aforesaid Merritt Patent 1,041,652, 20 the construction being such that the upper movable blade 46 bears upon the upper surface of fixed blade 43 and, with its arm 47, participates in any upward movement of the presser-foot and of blade 43. To deflect to 25 one side the trimmings removed by the trimmer-blades, a deflector 48 is pivoted by a screw 49 to toe 41. It may be swung outward on said pivot-screw, from its normal position shown in Fig. 1, to give access to the 30 thread manipulating elements.

50 (Figs. 1, 5 and 6) is a needle-opening through the presser-foot. 51 (Figs. 1, 3 and 5) is a chaining-foot positioned in an opening through the foot to the rear of said needle-opening, the same as shown in the patents aforesaid. A stem 52 on said chaining-foot 51 projects upward into a socket of the foot-body 30, and is acted upon by a spring 53 (Fig. 3) to yieldingly hold the chaining-foot 35 to its work. A screw 54 threaded into stem 52 with its head movable in a slot in the wall of 30 limits the movement of the chaining-foot relative to the main foot. Any suitable feed may be used, either single, or double 40 differential, such as shown in the patents aforesaid. Fig. 2 shows a feed-member 55 working through cloth-plate 56 supported by a work-arm 57.

The structure as thus far described in detail is substantially that of the patents aforesaid, and for ordinary uses of sewing machines such as the aforesaid flatlock machine, constitutes a complete and efficient presser-foot. But, in operations upon fabric of materially different thicknesses under opposite sides of the foot—as where the edge of a single thickness of heavy fabric is to be abutted and joined to the edge of a double thickness of the same fabric—the lifting of the foot by the greater thickness of material under one side thereof interferes with the satisfactory engagement of the foot with the lesser thickness of material under the other side thereof, and consequently with the feed of the material or fabric by the feed-means. To adapt said

presser-foot to such conditions of different thicknesses, yielding bottom springs have been practically and commercially used prior to the present invention, said bottom springs being in the form of an attachment, or attachments, removably applicable to a presser-foot such as hereinbefore described, as will be more fully understood from the here following detailed description of such bottom springs.

60 is a bottom spring extending beneath the left-hand side of the foot proper lengthwise thereof. It is made of a flat strip of spring metal, preferably steel, slightly bowed along its middle and bent over at its opposite ends, similar to the runner of a boy's sled. The forward bent end 61 fits toe 42 of the foot and is secured thereto by a screw 62. The hooked rear end 63 of bottom 60 engages about the rear edge of the foot proper forming a loose connection thereto allowing freedom of longitudinal movement, as the bowed bottom is flattened more or less against the normal bottom surface of the foot proper, and also limited freedom of lateral movement. In addition to thus providing for attachment of the flat-spring bottom member to the foot proper, the rounded surfaces formed by the bending of the spring at both ends avoid angular edges to be passed by the material in its advance under the foot.

70 is a similar foot bottom extending beneath the right-hand side of the foot proper lengthwise thereof, secured at its forward bent end 71 to toe 41 by a screw 72, and at its rear hooked end 73 making loose connection to the rear edge of the foot proper, affording freedom of longitudinal and limited lateral movement relative thereto. The inner edges of the two flat-spring bottom members are so relatively shaped as to fit about the chaining-foot 51 and clear the needle-opening 50, said edges standing closest together at 64 and 74 just in front of said needle-opening, from whence they gradually diverge to their forward ends. A rod 90 hooked at both ends into engagement with the hooks 63 and 73 respectively of the flat spring bottom members, as clearly shown in Fig. 3, but omitted in Fig. 1, permits limited lateral movement of said bottom springs at their rear ends but prevents such movement to an extent sufficient to disengage either of said hooks 63 or 73 from the rear edge of the foot proper.

80 Prior to the present invention the flat bottom surface of the main body of the foot or foot proper 30—including the parts of said surface covered by the two bottom springs and also the parts thereof between the inner edges of said springs both in front of and in the rear of the needle opening—has all been in the same plane. With the bottom springs applied beneath said surface all in the same plane, a downwardly opening groove 90 is formed between the inner spaced edges of

the springs and that portion of said bottom surface of the foot proper which lies above said space between the edges of the springs. And even when both springs are pressed 5 firmly against said bottom surface of the foot body, such groove is present to a depth equal to the thickness of the metal of the springs and extending along the bottom of the foot from the inner end of the slot in the forward 10 portion of the foot up to and then past the needle opening. In the operation of the foot upon fabric, this shallow groove or space is positioned over the two edges of fabric which have been trimmed at the forward part 15 of the foot and which are to be abutted and sewed together at the rear portion of the foot, and said groove thus tends to permit said fabric edges to pass without being compressed and flattened to the maximum at their line of 20 abutment with a resulting tendency toward a slightly ridged seam.

According to the present invention, while the two portions 85 and 86 (Fig. 6) of the bottom surface of the body of the foot, or foot 25 proper 30, which portions 85 and 86 are covered by the bottom springs 60 and 70 respectively—are in a plane preferably higher than heretofore, a distance equal to the thickness of the metal of the springs, other portions 30 of the bottom surface of said foot proper not covered by the inner edges of the springs, are so formed as to lie in a plane at a lower level, lower to the extent of the thickness of the metal of the bottom springs. Thus the portion 35 87 in front of the needle opening and between the inner edges of the bottom springs, and the portion 88 at the rear of said needle opening and also between the inner edges of the bottom springs, are so formed as to both 40 stand in a plane below the level or plane of the surface portions 85 and 86 a distance equal to the thickness of the metal of the springs. This formation may be accomplished by welding or otherwise attaching pieces of metal to 45 constitute the portions 87 and 88, but preferably a single piece of metal constituting the main body of the foot, or at least the lower portion thereof, is cut away at its bottom to present the aforesaid relationship of surfaces 50 85, 86, 87, and 88; either way, there are bottom surface portions 87 and 88 fixed on the foot proper or main body of the foot.

As shown in Fig. 2, the presser foot is operating upon two thicknesses of material or fabric x and y under the left hand side thereof, to be joined by an abutted seam to a single thickness of material z under the right hand side thereof. The spring pressure exerted by the regular presser foot spring 81, being more powerful than the spring power of either, or both, spring bottoms 60 and 70, the flat bottom spring 60 in engagement with double thickness of material is flattened firmly into contact with the surface 85 (Fig. 6) of the body of the foot beneath which said spring

is positioned. At the same time the bottom spring 70, still slightly bowed outward from the portion 86 of the bottom of the main body of the foot over which said spring is positioned, makes firm yielding engagement with the single thickness of material under the right hand side of the foot, Fig. 2. The material or fabric so engaged is uniformly advanced under both sides of the foot by the feed (see feed member 55 of Fig. 2 for example) notwithstanding the different thicknesses. Obviously, if the two thicknesses of material were under the right hand side of the foot and the single thickness under the left hand side, the action of the flat spring bottom members would be reversed. In thus automatically accommodating itself to differences and variations in thickness of material, the presser foot is enabled to maintain a firm and distributed pressure upon the work against the cloth plate and feed members, and to afford an even feed at both sides of the seam regardless of differences and variations in the thickness of material.

As diagrammatically shown in Fig. 8, in operating upon like thicknesses of fabric under both sides of the presser foot, both bottom springs are pressed upward firmly into contact with the overlying portions of the bottom surface of the main body of the foot, and the bottom surfaces of both springs and portions 87 and 88 of the bottom surface of the main body of the foot, all stand in the same plane flush with each other. There is thus presented a practically continuous flat 90 surface extending across the line of abutment of the fabric edges both in front of and to the rear of the needle opening without groove or depression and acting to compress, compact or iron down the abutting edges and produce 95 a seam of maximum flatness free of any ridge effect. There is a similar functioning in forming an abutted seam joining greater to lesser thicknesses of fabric, except that in such case the bottom spring in engagement 100 with the lesser thickness of fabric or material stands below the level of the other spring and the bottom surfaces 87 and 88. An example of this is diagrammatically illustrated in Fig. 9, in joining two thicknesses of fabric under the left side of the foot to one thickness under the right side. The bottom spring 60 engaging the two thicknesses x and y is pressed upward into firm contact with the overlying portion 85 of the bottom surface of the main body of the foot, while the bottom spring 70 yieldingly engages the single thickness z at the other side of the foot at a lower level.

It is generally preferable to make a presser foot universally applicable to sewing equal 125 to equal or greater to lesser thicknesses of fabric edges, regardless of which side of the foot is to engage the greater thickness. To that end it is preferable to employ the two flat spring bottom members 60 and 70 at both 130

sides of the foot. But if in operating upon greater to lesser thicknesses of fabric, the lesser thickness is to be regularly presented under the same side of the foot, then the bottom spring may be omitted at the side of the foot which is to regularly engage the greater thickness. Under such condition that portion of the bottom of the main body of the foot not covered by the single bottom spring 10 could, in accordance with my present invention, be so formed as to stand in a plane below that portion of said bottom covered by the bottom spring, the distance below being equal to the thickness of the metal of the 15 spring, as diagrammatically shown for example in Fig. 10 which is a sectional view on a line corresponding to the line *a—a* of Fig. 5.

What is claimed as new is:—

20 1. In a presser foot, the combination of the foot proper or main body of the foot having a notch or slot extending rearwardly from the forward end thereof and in which upstanding fabric is adapted to be advanced and trimmed before it reaches the stitch forming parts; a horizontally operating trimming mechanism including relatively movable blades cooperating at their cutting edges in said notch to trim upstanding fabric advancing therein; two vertically yieldable flat 25 spring fabric engaging bottom members extending longitudinally beneath the foot body at opposite sides thereof and spaced apart at their inner edges; and a bottom surface fixed on the foot proper and positioned between the inner edges of said flat spring bottom members to the rear of the needle opening and adapted to flush the bottom surface of either or both of said flat spring bottom members when the same are pressed upward 30 relative to the foot proper by engagement with fabric thereunder.

35 2. In a presser foot, the combination of the foot proper or main body of the foot having a notch or slot extending rearwardly from the forward end thereof and in which upstanding fabric is adapted to be advanced and trimmed before it reaches the stitch forming parts, said foot proper also having a needle 40 opening therein to the rear of said slot; a horizontally operating trimming mechanism including relatively movable blades cooperating at their cutting edges in said notch to trim upstanding fabric advancing therein; two vertically yieldable flat spring fabric engaging bottom members extending longitudinally beneath the foot body at opposite sides thereof and spaced apart at their inner edges; and a bottom surface on the foot proper positioned between the inner edges of said flat spring bottom members to the rear of said notch and in front of the needle opening in the foot proper and adapted to flush the bottom surface of either or both of said flat spring bottom members when the same are pressed up- 45

ward relative to the foot proper by engagement with fabric thereunder.

3. In a presser foot, the combination of the foot proper or main body of the foot having a notch or slot extending rearwardly from the forward end thereof and in which upstanding fabric is adapted to be advanced and trimmed before it reaches the stitch forming parts, said foot proper also having a needle opening therein to the rear of said slot; a horizontally operating trimming mechanism including relatively movable blades cooperating at their cutting edges in said notch to trim upstanding fabric advancing therein; two vertically yieldable flat 50 spring fabric engaging bottom members extending longitudinally beneath the foot body at opposite sides thereof and spaced apart at their inner edges; and a bottom surface fixed on the foot proper and positioned between the inner edges of said flat spring bottom members to the rear of the needle opening and adapted to flush the bottom surface of either or both of said flat spring bottom members when the same are pressed upward 55 relative to the foot proper by engagement with fabric thereunder.

4. In a presser foot, the combination of the foot proper or main body of the foot having a notch or slot extending rearwardly from the forward end thereof and in which upstanding fabric is adapted to be advanced and trimmed before it reaches the stitch forming parts, said foot proper also having a needle opening therein to the rear of said slot; a horizontally operating trimming mechanism including relatively movable blades cooperating at their cutting edges in said notch to trim upstanding fabric advancing therein; two vertically yieldable flat 60 spring fabric engaging bottom members extending longitudinally beneath the foot body at opposite sides thereof and spaced apart at their inner edges; and a bottom surface fixed on the foot proper and positioned between the inner edges of said flat spring bottom members to the rear of the needle opening and adapted to flush the bottom surface of either or both of said flat spring bottom members when the same are pressed upward 65 relative to the foot proper by engagement with fabric thereunder.

5. In a presser foot, the combination of the foot proper or main body of the foot having a notch or slot extending rearwardly from the forward end thereof and in which upstanding fabric is adapted to be advanced and trimmed before it reaches the stitch forming parts; a horizontally operating trimming mechanism including relatively movable blades cooperating at their cutting edges in said notch to trim upstanding fabric advancing therein; a vertically yieldable flat spring fabric engaging bottom member extending longitudinally beneath the foot body at one 70

side thereof; and a bottom surface fixed on the foot proper and positioned to the rear of the notch and bordered by the inner edge of said bottom spring and adapted to flush the bottom surface of said bottom spring when the same is pressed upward relative to the foot proper by engagement with fabric thereunder.

6. In a presser foot, the combination of the foot proper or main body of the foot having a notch or slot extending rearwardly from the forward end thereof and in which upstanding fabric is adapted to be advanced and trimmed before it reaches the stitch forming parts, said foot proper also having a needle opening therein to the rear of said slot; a horizontally operating trimming mechanism including relatively movable blades cooperating at their cutting edges in said notch to trim upstanding fabric advancing therein; a vertically yieldable flat spring fabric engaging bottom member extending longitudinally beneath the foot body at one side thereof; and a bottom fixed surface of the foot proper positioned to the rear of the needle opening and adapted to flush the bottom surface of said bottom spring when the same is pressed upward relative to the foot proper by engagement with fabric thereunder.

7. In a presser foot, the combination of the foot proper or main body of the foot having a notch or slot extending rearwardly from the forward end thereof and in which upstanding fabric is adapted to be advanced and trimmed before it reaches the stitch forming parts, said foot proper also having a needle opening therein to the rear of said slot; a horizontally operating trimming mechanism including relatively movable blades cooperating at their cutting edges in said notch to trim upstanding fabric advancing therein; a vertically yieldable flat spring fabric engaging bottom member extending longitudinally beneath the foot body at one side thereof; and a bottom surface on the presser foot proper positioned to the rear of said notch and in front of said needle opening and adapted to flush the bottom surface of said bottom spring when the latter is pressed upward relative to the foot proper by engagement with fabric thereunder.

8. In a presser foot, the combination of the foot proper or main body of the foot having a notch or slot extending rearwardly from the forward end thereof and in which upstanding fabric is adapted to be advanced and trimmed before it reaches the stitch forming parts, said foot proper also having a needle opening therein to the rear of said slot; a horizontally operating trimming mechanism including relatively movable blades cooperating at their cutting edges in said notch to trim upstanding fabric advancing therein; two vertically yieldable fabric engaging bottom members extending longitudinally beneath the foot body at opposite sides thereof and spaced apart at their inner edges; and a bottom surface fixed on the foot proper and positioned between the inner edges of said yieldable bottom members to the rear of the needle opening and adapted to flush the bottom surface of either or both of said yieldable bottom members when the same are pressed upward relative to the foot proper by engagement with fabric thereunder.

tudinally beneath the foot body at opposite sides thereof and spaced apart at their inner edges; and a bottom surface fixed on the foot proper and positioned between the inner edges of said yieldable bottom members to the rear of said notch in the foot proper and adapted to flush the bottom surface of either or both of said yieldable bottom members when the same are pressed upward relative to the foot proper by engagement with fabric

75

9. In a presser foot, the combination of the foot proper or main body of the foot having a notch or slot extending rearwardly from the forward end thereof and in which upstanding fabric is adapted to be advanced and trimmed before it reaches the stitch forming parts, said foot proper also having a needle opening therein to the rear of said slot; a horizontally operating trimming mechanism including relatively movable blades cooperating at their cutting edges in said notch to trim upstanding fabric advancing therein; two vertically yieldable fabric engaging bottom members extending longitudinally beneath the foot body at opposite sides thereof and spaced apart at their inner edges; and a bottom surface on the foot proper positioned between the inner edges of said yieldable bottom members to the rear of said notch and in front of the needle opening in the foot proper and adapted to flush the bottom surface of either or both of said yieldable bottom members when the same are pressed upward relative to the foot proper by engagement with fabric thereunder.

100

10. In a presser foot, the combination of the foot proper or main body of the foot having a notch or slot extending rearwardly from the forward end thereof and in which upstanding fabric is adapted to be advanced and trimmed before it reaches the stitch forming parts, said foot proper also having a needle opening therein to the rear of said slot; a horizontally operating trimming mechanism including relatively movable blades cooperating at their cutting edges in said notch to trim upstanding fabric advancing therein; two vertically yieldable fabric engaging bottom members extending longitudinally beneath the foot body at opposite sides thereof and spaced apart at their inner edges; and a bottom surface fixed on the foot proper and positioned between the inner edges of said yieldable bottom members to the rear of the needle opening and adapted to flush the bottom surface of either or both of said yieldable bottom members when the same are pressed upward relative to the foot proper by engagement with fabric thereunder.

110

11. In a presser foot, the combination of the foot proper or main body of the foot having a notch or slot extending rearwardly from the forward end thereof and in which upstanding fabric is adapted to be advanced

125

130

- and trimmed before it reaches the stitch forming parts, said foot proper also having a needle opening therein to the rear of said slot; a horizontally operating trimming mechanism including relatively movable blades cooperating at their cutting edges in said notch to trim upstanding fabric advancing therein; a vertically yieldable fabric-engaging bottom member extending longitudinally beneath the foot body at one side thereof; and a bottom surface fixed on the foot proper and positioned to the rear of the notch and bordered by the inner edge of said vertically yieldable fabric-engaging bottom member and adapted to flush the bottom surface of said yieldable member when the latter is pressed upward relative to the foot proper by engagement with fabric thereunder.
- 10 12. In a presser foot, the combination of the foot proper or main body of the foot having a notch or slot extending rearwardly from the forward end thereof and in which upstanding fabric is adapted to be advanced and trimmed before it reaches the stitch forming parts, said foot proper also having a needle opening therein to the rear of said slot; a horizontally operating trimming mechanism including relatively movable blades co-
25 operating at their cutting edges in said notch to trim upstanding fabric advancing therein; a vertically yieldable fabric-engaging bottom member extending longitudinally beneath the foot body at one side thereof; and
30 a bottom surface fixed on the foot proper and positioned to the rear of the notch and in front of the needle opening in the foot proper and bordered by the inner edge of said vertically yieldable fabric-engaging bottom member and adapted to flush the bottom surface of said yieldable member when the latter is pressed upward relative to the foot proper by engagement with fabric thereunder.
- 35 13. In testimony whereof I have signed this specification.

GILBERT LAWRENCE SUMMERS.
